Specification for Design.

Patented July 2, 1918.

Application filed April 25, 1918. Serial No. 230,813. Term of patent 14 years.

To all whom it may concern:

Be it known that I, WILLIAM J. GAGNON, a citizen of the United States of America, residing at Bridgeport, in the county of Fairfield and State of Connecticut, have invented a new, original, and ornamental Design for a Jump-Ring Coupling, of which the following is a specification, reference being had to the accompanying drawing, forming part hereof.

The drawing shows in—

Figure 1 a side elevation of a jump ring coupling in which my new design is embodied;

Fig. 2 is an elevation at right angles to Fig. 1;

Fig. 3 is a bottom plan view thereof; and Fig. 4 is a top plan view thereof.

I claim:—

The ornamental design for a jump ring coupling, substantially as shown.

WILLIAM J. GAGNON.
